UNITED STATES PATENT OFFICE.

ALFRED HAIGH, OF STAFFORDSHIRE, ENGLAND.

PROCESS OF MAKING CARBON AND OTHER COATED PAPERS.

No Drawing.

Application filed September 7, 1922. Serial No. 586,772.

To all whom it may concern:

Be it known that I, ALFRED HAIGH, a subject of the King of Great Britain, residing in Staffordshire, England, have invented 5 certain new and useful Improvements in Processes of Making Carbon and Other Coated Papers, of which the following is a specification.

This invention relates to improvements 10 in and relating to carbon and other coated papers and carbonizing papers and refers primarily to the so-called carbon papers such as are used for duplicating purposes upon typewriting machines in salesmen's books 15 and for other purposes and in which one or both sides or surfaces are coated with the desired composition.

The present invention relates to papers 20 of the above character in which only one side or surface is coated.

The term "carbonizing papers" used herein is intended to apply to the plain or untreated paper.

In the manufacture of carbon papers as 25 at present generally conducted the paper in the form of a continuous web of thin paper is first coated and afterwards cut up into sheets of the desired dimensions.

In view of the thinness of the paper a certain amount of care is required in the handling thereof in order to avoid tearing or 30 damaging same, and further care is necessary to prevent the composition from getting upon that side of the paper which is to remain untreated.

Where a thin paper is employed, such as that referred to, it frequently happens that there are small holes in said paper through which the coating material will pass to the 40 back of the sheet and extend more or less thereover, in which case not only does the paper stick to the rollers but the coating composition thus conveyed to the rollers will "set off" or stain the paper which follows.

The present invention has for its object 45 to overcome the aforesaid objections attending the present method of manufacture of carbon papers, and further to simplify and expedite the production of such paper.

According to the present invention instead 50 of employing a single sheet of paper two sheets are employed which are secured together throughout the whole of their contacting surfaces in any suitable manner such 55 as will enable them to be afterwards readily separated, one or both of the outer surfaces

of both sheets receiving a coating of the desired composition.

The composition can be applied first to one side of the paper and then to the other 60 in two separate operations or both sides of the paper may be simultaneously coated by any of the methods employed or capable of being employed for producing a double sided carbon paper. 65

By this means two carbon sheets may be produced instead of one, and further any risk of the composition passing through holes in the paper and extending to the uncoated surface is prevented. 70

The papers may be both of the same weight or thickness or one paper may be heavier than the other.

The attachment of the papers one to another may be effected by bringing the sheets 75 or webs of paper together whilst one is in a moist condition and causing them to adhere by pressure.

The utility of the present invention lies not only in the reduction of cost when the 80 two papers are coated together but also in the greater ease with which the double paper is handled, and further again in that when this invention is used there is no possibility of surplus composition deposited accidentally. 85

Another use may, if preferred, be made of this present invention by coating only one of the two papers. 90

In this case the second advantage is entirely secured and the third advantage is partially secured inasmuch as the second paper covers any pin-holes on the paper which is being coated. 95

If desired this second paper may be left on the carbon paper as distributed or used thus acting as a fixed interleaving paper.

Any other coating process besides carbonizing may be used or applied to this paper. 100

Claims:

1. A process including superposing face to face webs of thin carbonizing paper suitable for making typewriter carbon paper; expressing the air from between said webs; 105 moistening the webs and causing the superposed webs to intimately cohere at the edges thereof and continuously from edge to edge throughout in a manner to permit the ready separation of the webs without tearing the 110 webs, and in a manner to seal pin holes in the webs and to prevent the inflow of car-

bonizing coating material between the webs through the web or at the edges thereof; coating the exposed faces of said webs with carbonizing coating material while the 5 papers are thus intimately superposed; and permanently separating the webs.

2. A process including moistening and superposing webs of paper; pressing said webs together for causing said webs to cohere in a manner to permit ready separation 10 of the webs; and while the webs are still cohered coating the exposed face of one of the webs with carbon for forming copying paper.

15 3. The herein described process for coat-

ing paper which consists in moistening two webs of paper, placing the webs while in moist condition the one upon the other and pressing them together to cause the webs to adhere the one to the other throughout the 20 whole of their contacting surfaces for the full length of the webs in such manner as to permit subsequent separation of the webs, and applying the coating to the outer surface of one of the webs while the webs are 25 adhered together.

In testimony whereof I have hereunto set my hand.

ALFRED HAIGH.
